COMBINED HINGE AND LATCH MOUNTING

Homer H. Cohn, Yuba City, Calif., assignor of
 ninety per cent to Lloyd Hamner, Bertine L.
 Hamner, Loyd Mulkey, and Nora L. Mulkey, all
 of Yuba City, Calif.

Application December 14, 1949, Serial No. 132,825

2 Claims. (Cl. 16—147)

1

This invention relates to a door mounting, and more particularly to a door mounting which will permit a door to be either swung open from the left or right side.

The object of the invention is to provide a door mounting whereby a door, such as a door for a refrigerator or cabinet, may be swung open from either vertical edge.

Another object of the invention is to provide a door mounting which permits the door to be opened from either side, yet prevents the door from being opened from both sides at the same time, and wherein a means is provided for releasably latching the door in its closed position.

A further object of the invention is to provide a door mounting which is extremely simple and inexpensive to manufacture.

Other objects and advantages will be apparent from the following description.

In the accompanying drawings forming a part of this application, and in which like numerals have been used to designate like parts throughout the same:

Figure 1 is a front elevational view showing a cabinet or refrigerator provided with the door mounting of the present invention, the door being in one of its open positions;

Figure 2 is an enlarged fragmentary front elevational view showing certain constructional details of the door mounting actuating mechanism;

Figure 3 is a sectional view taken on the line 3—3 of Figure 2;

Figure 4 is a fragmentary top plan view of the actuating mechanism;

Figure 5 is a sectional view taken on the line 5—5 of Figure 2.

Referring in detail to the drawings, the numeral 10 designates a cabinet or refrigerator which is provided with an inner compartment 11 for the storage therein of food or other articles. A door 12 is mounted for swinging movement about a vertical axis. The present invention is directed to a mounting for the door 12, whereby the door 12 can be opened from either side of the cabinet 10. Further, by means of the construction of the present invention, it will be impossible to open the door from both sides at the same time. Also, there is provided a means for maintaining the door releasably latched in its closed position.

The door mounting includes an actuating mechanism which embodies a plate 14 that extends transversely across the door 12 and is secured thereto in any suitable manner. Arranged

2

in spaced parallel relation with respect to the plate 14 is an actuating bar 15, and the bar 15 is provided with a slot 16 intermediate its ends for a purpose to be later described. A pin 17 pivotally connects one end of the bar 15 to a bell crank 18, and a pin 20 pivotally connects the other end of the bell crank 18 to the lower end of a lock bolt 19. The bell crank 18 is pivotally connected to the plate 14 by means of a pin 10 21.

The other end of the bar 15 is pivotally connected to one end of a second bell crank 23 by means of a pin 22, while the other end of the bell crank 23 is pivotally connected to a movable lock bolt 25 by means of a pin 24, Figures 1 and 2. A pin 26 pivotally connects the bell crank 23 to the plate 14.

Pivots connected to the plate 14 is a pair of spaced latches 27 and 28. Thus, a pin 29 serves to pivotally connect the latch 27 to the plate 14, and a similar pin 30 is provided for pivotally connecting the other latch 28 to the plate 14. Each of the latches 27 has the same construction and each includes a pointed end 31 that is mounted for movement into and out of engagement with the slots 16 in the actuating bar 15. A coil spring 32 serves to connect the pair of latches 27 and 28 together.

Also pivotally connected to the plate 14 is a pair of pawls 33 and 34. Thus, each of the pawls 33 and 34 is connected to one end of a shaft 35, the shaft 35 being rotatably positioned in a bearing sleeve 36. A handle 37 is secured or connected to one end of each of the shafts 35 for rotating the shafts to thereby selectively rotate or pivot the pawls 33 and 34. The pawls 33 and 34 are adapted to be pivoted into and out of engagement with the bell cranks 18 and 23, as later described in this application.

Carried by the pawl 33 is a spring member 38, 40 and by properly rotating the pawl 33, the spring member 38 can be used to move the pointed end 31 of the latch 27 into the slot 16. A similar spring member 39 is secured to the other pawl 34, whereby upon proper movement of the pawl 45 34, the spring member 39 will move the latch 28 into the opposite portion or end of the slot 16. The spring 32 normally serves to urge the latches 27 and 28 out of the slot 16 and into their positions shown in Figure 2. A coil spring 40 has one of its ends connected to the pawl 33, while the other end of the coil spring 40 is connected to the other pawl 34, the coil spring 40 tending to normally urge the pawls 33 and 34 into their normal positions, as shown in Figure 2.

Projecting inwardly from the bar 15 is a pair

of spaced parallel lugs or pins 41 and 42. The lugs 41 and 42 are adapted to be engaged or contacted by the pawls 33 and 34 to limit inward or clockwise pivotal movement of the pawls 33 and 34. Projecting from one end of the plate 14 and secured thereto is a pair of horizontally disposed, spaced parallel, apertured fins 43 and 44 which are each provided with an aligned opening 45 for the passage therethrough of the lock bolt 19. Arranged in spaced parallel relation below the fin 44 is an additional fin 46 which also has an opening that is arranged in registry or alignment with the openings 45. The lock bolt 19 also slidably projects through the guide fin 46 so as to insure that the lock bolt 19 is maintained in alignment during its movement. A guard shield 47 surrounds the movable lock bolt 19 so as to prevent any accidental interference with the moving parts. A coil spring 48 has one end connected to the fin 46, while the other end of the coil spring 48 is connected to the bell crank 18. The coil spring 48 tends to normally urge the lock bolt 19 into its raised position, as shown in Figure 2.

Secured to the other end of the plate 14 is a similar pair of horizontally disposed, spaced parallel fins 49 and 50. Each of the fins 49 and 50 is provided with an aligned opening 51 for the projection therethrough of the locking pin 25. A fin 52 is arranged below the fin 50, the fin 52 serving the same purpose as the other fin 46. A coil spring 53 is provided for normally urging the other locking pin 25 into its raised position. A guard shield 54 surrounds the locking pin 25 so as to prevent accidental interference therewith.

Secured to one side of the cabinet 10 is a hinge bracket 55, while arranged in alignment with the hinge bracket 55 and secured to the other side of the cabinet 10 is a similar hinge bracket 56. Each of the hinge brackets 55 and 56 includes a vertically disposed bore 57 for selectively receiving therein the locking bolts and the hinge brackets 55 and 56 are also provided with internal bearings so as to insure the smooth movement of the lock bolts 19 and 25 therethrough. The hinge bracket 55 is adapted to be straddled or embraced by the pair of fins 49 and 50, while the other hinge bracket 56 is adapted to be straddled by the other pair of fins 43 and 44. Arranged below the hinge bracket 55 and secured to the cabinet 10 is a guide hinge member 58. Secured to the door 12 is an arcuate finger or strip 59 which is adapted to engage the hinge member 58. Similarly, arranged below the hinge bracket 56 and secured to the cabinet 10 is a hinge bracket 60. An arcuate finger or strip 61 is secured to the other side of the door 12 and the finger 61 is adapted to engage with the hinge member 60. Each of the hinge members 58 and 60 is of the same construction, and each includes a roller 62 that is adapted to be slidably engaged by the corresponding finger 59 or 61.

In use, articles of food or other goods can be stored in the compartment 11 and the door 12 is normally in its closed position to protect the articles therein. Then, by means of the mounting of the present invention, the door 12 can be swung open about either vertical axis. Thus, for example, to open the door 12 to the position shown in Figure 1, the proper handle 31 is rotated in a counterclockwise direction to thereby pivot the pawl 33 from the position shown in Figure 2 to the position shown in Figure 1. As the pawl

33 moves, it contacts the bell crank 18 to pivot the bell crank 18 in a counterclockwise direction, and this causes the lock bolt 19 to be lowered out of the bore in the hinge bracket 56. Simultaneously, as the pawl 33 is moved, it carries the spring, member 33 into engagement with the latch 27, whereby the pointed end 31 of the latch 27 is moved into the slot 16 in the bar 15, so as to hold the actuating bar 15 in its shifted position and also to hold the bolt 19 in its lowered position. Thus, it will be seen that the bolt 19 is now depressed or lowered out of the bore in the hinge bracket 56, so that the door 12 can be swung open to the position shown in Figure 1. The finger 61 is merely arranged in frictional engagement with the roller 62 of the hinge member 60 so that the parts 61 and 60 can readily separate.

It is to be noted that the strip 59 and hinge member 58 are now coacting to define the lower portion of the hinge connection between the door 12 and the cabinet 10. The upper portion of the hinge is defined by the lock bolt 25 which is slidably arranged in the bore in the hinge member 55. After the articles have been removed from the compartment 11, the door 12 is closed, and the handle is returned to its normal position, whereby the lock bolt 19 will be arranged, or urged into the bore in the hinge bracket 56 to releasably lock the door in its closed position. Similarly, the door 12 can be swung open about the other vertical axis by properly rotating the other handle to thereby rotate the bell crank 23 in a clockwise direction. Thus, this clockwise rotation of the bell crank 23 will depress the lock bolt 25 so that the door 12 is free to swing about the other vertical axis of the cabinet 10.

The coil springs 48 and 53 tend to normally urge the lock bolts into their raised positions. The elongated coil spring 49 which is connected to the pair of pawls 33 and 34 serves to normally urge the pair of pawls into their normal positions, as shown in Figure 2. Further, the coil spring 32 insures that the latches 27 and 28 will drop out of the slot 16 at the proper time.

From the foregoing, it is apparent that a door mounting has been provided whereby a door for a refrigerator or cabinet can be opened from either side, and yet the door will be prevented from being opened from both sides at the same time. Further, the mounting includes a means for releasably locking the door in its closed position. The door will operate smoothly and efficiently, and it will be impossible to inadvertently unlock both sides at the same time. The device is simple and easy to construct and has a minimum of moving parts. The cabinet equipped with the door mounting of the present invention is neat in appearance and the cabinet or refrigerator can be placed in a corner of a kitchen or other confined space whereby the door can be conveniently swung open from either side.

The door mounting further includes a pair of spring blades 65 and 66 which are each secured to the upper portion of the plate 14 by suitable securing elements, such as screws 67. The spring blades 65 and 66 are flexible so that as the lock bolts 19 or 25 are moved to their lowermost position by means of the handles, the free end of the spring blades 65 or 66 will move out directly over the lowered lock bolt. These spring blades will thus serve to insure that the lock bolts 19 and 25 do not accidentally move upwardly until the door is closed. When the door is moved to its closed position, the spring blades are forced

back against the plate 14 so as to permit the proper lock bolt to be raised.

I claim:

1. In a mounting for a swinging door, a plate adapted to extend transversely across the door and be supported thereby, an actuating bar arranged in spaced parallel relation with respect to said plate, there being a slot arranged intermediate the ends of said bar, a pair of bell cranks pivotally connected to said plate and interposed between said plate and bar, a pair of pawls pivotally connected to said plate, handles connected one to each of said pawls for rotating the latter, resilient means connecting said pair of pawls together, a pair of spaced latches pivotally connected to said plate and mounted for movement into and out of said slot, resilient means connecting said pair of latches together, spring members one carried by each of said pawls for causing moving of said latches into said slot, a plurality of spaced parallel horizontally disposed apertured fins secured to one end of said plate,

a plurality of similar fins secured to the other end of said plate, a pair of lock bolts one being slidably arranged in each of said pluralities of apertured fins and pivotally connected to a different one of said bell cranks, resilient means connecting the lowermost of each of said pluralities of fins to the complementary bell crank, and a pair of aligned hinge brackets adapted to be secured one to each of the opposite sides of a cabinet for selectively receiving said locking bolts

2. The apparatus as described in claim 1 wherein each of said resilient means embodies a coil spring.

HOMER H. COHUN.
